United States Patent Office.

NICHOLAS S. VEDDER, OF TROY, AND TOBIAS S. HEISTER, OF LANSINGBURG, NEW YORK, ASSIGNORS TO NICHOLAS S. VEDDER.

Design No. 4,245, dated July 19, 1870.

DESIGN FOR STOVE-PLATES.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer and State of New York, have jointly invented and produced certain new and original features in Designs for Stoves-Plates, of which the following is a specification, reference being had to the accompanying photographic representation of a cooking-stove, having our new design.

One new feature of our said design is the compound ornament N, having the various parts thereof shaped and arranged together, and disposed upon and cast with a plate or plates, or a door or doors, of a stove, as represented in the aforesaid photograph.

Another feature of our said design is the combination of the compound ornament N, and an ornamental border molding, O, all shaped and arranged upon and cast with a door or doors, or a plate or plates of a stove, with or without an intervening molding, p, as shown in and by the aforesaid photographic representation.

Another new feature of our invention is the ornamental design for the foot Q, of a stove, as shown in the accompanying photograph.

What we claim as our invention and production, and desire to secure by Letters Patent, is—

1. The compound ornament N, arranged upon and cast with a plate or plates of a stove, as herein shown and described.
2. The combination of the compound ornament N, and ornamental border molding O, arranged together and cast upon a door or doors, or a plate or plates of a stove, as described and shown.
3. The design for the foot Q, as shown.

NICHOLAS S. VEDDER.
TOBIAS S. HEISTER.
